UNITED STATES PATENT OFFICE.

HENRY A. RUETER, OF BOSTON, MASSACHUSETTS.

BAR-INDICATOR FOR PREVENTING FRAUD IN DISPENSING BEVERAGES.

SPECIFICATION forming part of Letters Patent No. 793,232, dated June 27, 1905.

Application filed April 18, 1904. Serial No. 203,601.

To all whom it may concern:

Be it known that I, HENRY A. RUETER, a citizen of the United States, and a resident of Boston, in the Commonwealth of Massachusetts, have invented an Indicator Apparatus for Preventing Frauds in Dispensing Beverages, of which the following is a specification.

My invention resides in providing means for enabling the customer at a bar to know that he is being served with the genuine beverage that he calls for.

One of the long-recognized frauds, which it has seemed practically impossible to counteract, is the imposition upon the customer of a fraudulent beverage instead of the one he calls for, the regular custom being to have a series of faucets just beneath the back edge of the counter or bar out of sight, each faucet controlling a particular kind or brand of ale or other beverage, so that when the customer calls for any particular brand or kind he has no means of knowing whether the proper liquor is being drawn from the proper faucet or not. Various devices have been suggested; but notwithstanding the ingenuity devoted to this subject there has been, so far as I am aware, no means yet provided which accomplishes the desired result. Accordingly, to secure the desired result I take advantage of

two elements—viz., the desire of the customer to get what he orders and the desire of the brewer to have his product delivered when called for, these two elements being availed of by providing, in connection with the piping, &c., from the cellar or other remote place containing the separate sources of supply for the various bar-faucets, a series of indicators securely connected in such a manner that whenever the bartender draws any liquor the act of operating the faucet for that particular liquor will cause a conspicuous and startling movement of the special indicator provided for that liquor or faucet. By thus forcibly attracting the attention of the customers the public is quickly educated to watch for the proper signal, being thereby led to recognize and rely upon the signal as an aid in getting what they want, and by securely connecting the signals to operate in connection with the piping system the brewer (because of the difficulty and

time required in changing the source of supply of any given pipe) has at hand a ready and sure means of detecting any attempt at fraud simply by sending in at unexpected intervals a teamster or other representative to see that the source of supply has not been altered and corresponds to the signal at the bar.

My invention aims to induce the customers and manufacturer to coöperate in detecting and preventing fraud, the customers being led to watch for the conspicuous movement of the proper indicator, as stated, and the manufacturer relying on the difficulty of altering the connections between said indicator and the source of supply in the short interval between the inspection of the indicator by his representative and the time when he could get down cellar or wherever the kegs or other sources of supply are kept to examine the arrangement and connections thereof.

I prefer to attach the indicator directly to the handle of the faucet, so as to form a part thereof, so that it is visible when the faucet is closed, but disappears in the act of opening the faucet.

In the drawings, in which I have shown a preferred embodiment of my invention, Figure 1 is a front elevation or a fragmentary portion of an ordinary bar, representing my invention in use. Fig. 2 is a perspective view thereof from the rear side of the bar. Fig. 3 is an enlarged detail in side elevation and partly in section.

For convenience of illustration I have shown an ordinary liquor-dispensing bar comprising an upright portion a , terminating in a rail a' at its front side, and a counter portion or bar proper, a^2 , beneath which the faucets a^3 , a^4 , a^5 , &c., are located, connected by suitable pipes a^6 to the kegs or separate sources of supply. (Not shown.) Beneath the faucets is a usual drainage-rack a^7 , on which the glasses or mugs are placed. As ordinarily arranged the faucet is just beneath the rear edge of the counter a^2 and is provided with an ordinary operating-handle, as indicated at a^8 , which also terminates beneath the counter entirely out of sight, the result being that when a customer at the rail a' calls, for instance, for any given brand of ale the attendant or bartender operates any

 faucet he may desire and the customer has no means of knowing from which faucet he is being served. This works not only a fraud upon the customer, but a still greater fraud upon 5 that manufacturer who is conscientiously trying to give the best product and build up his business by means of the merits of the goods he sells. By my invention I prevent this fraud not by a mere label or sign, (as I make 10 no claim to a label *per se*,) but by providing a label or signal in such a position and so combined with other mechanism that it tends to engage the attention of the usually inattentive customer, who is thereby gradually educated 15 or insensibly induced to look for the said indicator and call for his beverage either by naming or pointing to said indicator, which therefore becomes his reliance, and because of its mechanical connection, location, 20 and arrangement (which make it convenient also for the manufacturer readily to detect and prevent attempted imposition) the customer soon becomes trained to note the appearance or disappearance or other radical and conspicuous change in position of the indicator. 25 One of the essential characteristics of my invention is the provision of means for attracting the notice and riveting the attention of the customer, and while this result may be 30 accomplished in various ways without departing from the spirit and scope of my invention I prefer to accomplish it by a sudden or bold movement of the indicator sufficiently startling and conspicuous to lead the customer 35 to notice the same. In this respect I wish to distinguish clearly from a mere label or sign commonly affixed or engraved on bottles and faucets for indicating either the contents or whether the faucet is open or closed, where 40 the label is either entirely stationary or remains in substantially the same position all the time, its movement, if any, being so slight as not to attract attention. Also my invention is to be distinguished from a mere 45 tag or label sometimes connected with the self-closing stopper of a portable syrup-jar or the like. My invention operates in connection with high-pressure apparatus, (ale, for instance, having upward of eighty pounds 50 pressure of carbonic gas per square inch,) and the faucet, operating means, and indicator are all so constructed and connected with the pressure-pipes as to be unaffected by the high pressure within the pipe connection, being in this 55 respect independent of said pressure, while giving visual assurance with absolute certainty that the correct faucet is being operated. Accordingly, as herein shown, I extend the handle of the faucet, as indicated at a^3 , so 60 that its upper end will project considerably above the counter a^2 , and at its upper end I provide a distinguishing device which serves to indicate the particular brand controlled by that faucet. For example, I may provide a 65 knob a^{10} , having a flattened face, on which

some indicating device may be stamped, as indicated by the letter A or the cross shown in Fig. 1, or, if desired, the name of the maker of the brand may be stamped thereon, or the brand may be known by the color or by any 70 other distinguishing medium, the main idea being to have the indicator extend within visual and conspicuous range of the customer, so that he will instinctively recognize the indicator and rely thereon in his selection and 75 will also learn to watch for the depression thereof as a means of knowing that his order is being filled properly.

I make no claim to the faucet, as any kind of faucet may be used, my invention residing 80 in no particular feature or element, but in combining the parts in such a manner that the indicator (which is permanently connected with the faucet) will in the first place be visible at one time and not visible, or at least 85 conspicuously and startlingly changed, at another time, according as it is being used or not used, and will in the second place be sufficiently conspicuous and distinctive or attractive (such as the manufacturer's name, 90 trade-mark, or other insignia of origin, as shown) to command the attention of the customer, so that he will naturally rely thereon.

Let it be supposed that an ordinary bar is provided with my invention. The result is 95 that instead of having the respective brands concealed and their relation to one another entirely unknown to the customer a series of indicators $a^{10} a^{10}$ will stand prominently in the range of the customer to challenge his notice 100 and to enable him to select that particular brand of beverage which he desires. Having ordered the same, it becomes necessary for the bar server to grasp that particular handle and depress the same in the sight of the customer, 105 who is thereby sure of fair treatment, the bar server is prevented from working a fraud, and the manufacturer is likewise protected. All concerned have in this invention a silent detective, rendering fraud so readily apprehended as to prevent the probability of its 110 being attempted. It is a very simple matter for the manufacturer to send an inspector to watch the piping of his beverage, and thereby prevent fraud by that means, whereas it 115 would be impossible for him to prevent fraud by the old system of faucets, as indicated at a^3 . The fact that the manufacturer's inspector is liable to call unexpectedly, coupled with the fact that the parts are permanently 120 connected, so that they cannot be readily changed or improperly manipulated by the bar attendant as the inspector approaches, render the bar attendant cautious, and as the indicator is so constructed as to be moved de- 125 cidedly whenever the faucet is operated, thereby conspicuously showing to the customer which faucet is operated, it becomes impracticable to attempt any fraud.

Having described my invention, what I 130

claim as new, and desire to secure by Letters Patent of the United States, is—

1. The herein-described means for mechanically employing trade-marks or other insignia of origin in connection with high-pressure beverage-dispensing apparatus for securing and promoting the coöperation of the customers and the beverage manufacturers in preventing fraud in dispensing the beverages, 5 consisting of the combination with a bar, having a stationary pipe connection with a remote source of beverage-supply, and a high-pressure dispensing-faucet located in said pipe at the bar, of an indicator, located always between the attendant and the customer, containing the manufacturer's name, trade-mark, or other distinctive and attractive insignia denoting origin, and indicator-operating means for conspicuously visually altering the indicator in such a manner as forcibly to attract the customer's attention, said faucet and operating means operating independently of and unaffected by the high pressure within said pipe connection, said operating means including permanent connection with the faucet for automatically actuating the indicator in the act of operating the faucet, and thereby prevent fraud as described.

2. As a means of preventing fraud in dispensing beverages under high pressure, the combination with a bar, having a plurality of adjacent stationary pipe connections for drawing respectively different beverages under high pressure from remote sources of supply, 35 each pipe having its own independent high-pressure dispensing-faucet located at the bar, of indicators arranged side by side at the bar within the direct visual range of the customer when being operated under normal conditions by the attendant, and each containing the manufacturer's name, trade-mark, or other distinctive and attractive insignia denoting origin of the particular high-pressure beverage indicated thereby, and indicator-operating means for each indicator, connecting it with its individual faucet, for conspicuously altering the indicator in such a manner as forcibly to attract the customer's attention in the act of operating the faucet, said faucets 45 and operating means being capable of operating independently of and unaffected by the high pressure controlled by the faucets.

3. The combination with a bar, of a faucet below said bar, and an indicator connected

thereto to move into sight above said bar and 55 to disappear from sight below said bar, said indicator being moved from one of said positions to the other in the act of operating the faucet.

4. As a means of preventing fraud in dispensing liquors, the combination with the bar or counter, of a faucet provided with a visual indicator normally extended prominently above the counter and depressed from the sight of the customer by the act of operating 65 the faucet.

5. As a means of preventing fraud in dispensing liquors, the combination with the bar or counter, of a faucet having an operating-handle provided with an upward extension, 70 whose upper end is provided with means for giving visual assurance that the correct faucet is operated, said means operating in the direct range of vision of the customer ordering a liquor, said means containing the trade- 75 mark or other insignia of origin of the particular liquor, the movement of the handle giving a wide amplitude of conspicuous movement to said trade-mark at the end of said extension, whereby the attention of the customer is drawn to said trade-mark and his coöperation is thereby enlisted to prevent 80 fraud.

6. As a means of preventing fraud in dispensing liquors, a plurality of signals having 85 different distinguishing characteristics in the nature of conspicuous marks of origin of the respective liquors, and having a position in sight and a position out of sight, and connected respectively to the different dispensing 90 devices, the movement of said signals from one of said positions to the other being such as to attract attention and induce the customer to scrutinize said marks of origin, whereby he is led to watch for the movement 95 of a given signal when ordering a corresponding liquor, and operating means for said signals, operated by the delivery of the liquor, for changing from one of said positions to the other the signal relating to the particular liquor being dispensed.

In testimony whereof I have signed my name to this specification in the presence of two subscribing witnesses.
